UNITED STATES PATENT OFFICE.

MARY L. WALTON, OF BARTOW, FLORIDA.

COMBINED STARCH-REMOVER AND HOLDER FOR IRONS.

1,263,971.

Specification of Letters Patent. Patented Apr. 23, 1918.

Application filed September 7, 1917. Serial No. 190,213.

To all whom it may concern:

Be it known that I, MARY L. WALTON, a citizen of the United States, residing at Bartow, in the county of Polk and State of Florida, have invented new and useful Improvements in Combined Starch-Removers and Holders for Irons, of which the following is a specification.

The present invention has reference generally to improvements in that class of inventions known as laundrying and more particularly relates to a combined starch remover and holder for irons.

This invention has for its principal aim and object to provide a device of the above character designed to serve as a support or holder for irons when temporarily not in use, and it is also constructed to remove starch from the under surface of the iron when the latter is moved thereacross.

As an additional object this invention embraces the provision of a device of the character mentioned wherein the construction embodies a roughened and perforated scraping surface supported in spaced relation to the base and over which the iron is moved to assure of the removal of starch therefrom.

More particularly, this invention contemplates the provision of a device of the above character embodying common means for supporting the perforated and roughened scraping surface in spaced relation to the base and for receiving the pieces of starch subsequent to their removal from the under surface of the iron.

Among the other aims and objects of this invention may be recited the provision of a device of the above character wherein the parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that

minor changes in the construction and arrangement of parts may be made without departing from the principle of operation of the various parts.

The invention is clearly illustrated in the accompanying drawings, in which:

Figure 1 is a top plan view;

Fig. 2 is a transverse section taken on line 2—2 of Fig. 1, in the direction in which the arrows point;

Fig. 3 is a transverse section taken on line 3—3 of Fig. 1 in the direction in which the arrows point;

Fig. 4 is a longitudinal section taken on line 4—4 of Fig. 1.

Similar characters of reference are employed in all of the above described views, to indicate corresponding parts.

Referring now, more particularly, to the accompanying drawings, there is provided a supporting base 1 which may be formed of any suitable material such as wood and preferably of a rectangular form. Rigidly secured through the instrumentality of suitable fastening devices 2 in the upper surface of the base are strips 3 of suitable material such as wood. These strips are arranged desirably in converging relation with each other to form a substantially inverted V at a point approximately centrally of the base and have their adjacent edges beveled toward each other as at 3', for a purpose that will hereinafter readily appear. A metallic plate 4 is now employed and is positioned transversely of the base above the strips, the respective side edges being secured to the base through the instrumentality of suitable fastening devices 5. Ribs 6 are preferably provided by bending the plate adjacent the side edges and by reason of the fact that the ribs are merely raised portions of the sheet they are arranged in a V-shape formed so as to straddle the strips 3, as indicated in Figs. 2 and 3. The space between the ribs constitutes a groove 7 for receiving pieces of starch that are deposited therein in the manner that will hereinafter become apparent.

With a view toward providing the improved scraping means for assuring of the removal of starch from the bottom of an iron, not shown, when the latter is moved thereacross, a piece of reticulated material 105 having also a roughened surface such as a

piece of screen 8 is employed and is preferably of a rectangular configuration, being bent adjacent its respective edges so that it may be readily fitted over the edges of the 5 metallic plate and secured to the upper surface of the base through the instrumentality of suitable fastening devices 9. In this connection it will be observed that that portion 10 of the screen between the two ribs is 10 maintained in a plane in substantially spaced parallel relation with respect to the plane of the upper surface of the base so that when an iron is moved thereacross the starch which usually adheres to the under surface 15 thereof will be removed therefrom and deposited into the groove 7.

Suitable means such as another piece of screen 11 is secured transversely across the intermediate portion of the plate, its respective ends being anchored to the upper 20 surface of the plate through the instrumentality of suitable fastening devices 12. This piece is of course secured preparatory to the securing of the piece of screen 8 and is desirably positioned through the ribs so as to 25 extend across the groove and in this manner serves to reinforce the portion 10 of the screen 8. In addition it is apparent that upon the moving of an iron across the upper 30 piece of screen 8 should any of the starch adhere thereto the yielding of this piece owing to the weight of the iron will enable the piece of screen 11 to act as a means for assuring of the removal of the starch from 35 the upper piece of screen 8 so that it will ultimately fall into the groove 7.

A cover plate 13 having a central opening 14 therein is now employed and is secured to the upper surface of the base about the 40 scraper through the instrumentality of suitable fastening devices 15. In this connection it will be observed that the opening permits of the arrangement of the plate in the proper position and in addition it may be 45 mentioned that the sides of the opening preferably converge toward each other so as to be properly fitted and lie in close relation with the outer sides of the ribs as indicated.

In use, it is to be appreciated that when an 50 iron, not shown, is temporarily idle it may be placed upon the supported scraping surface so that the edges thereof are arranged in substantial alinement with the outer side edges of the ribs until it is further desired 55 to use the iron. When it is desired to remove the starch from the under surface of the iron it is only necessary to move the same back and forth across the piece of screen 8 and during this action the pieces of 60 starch are scraped from the iron and passed between the pieces of screen 8 and 11 and are deposited in the groove 7. In this connection it will be observed upon reference to Fig. 4 that the bottom of the groove 7 is 65 preferably inclined from its restricted end

to its wider end so that the pieces of starch will be conducted toward the wider end when deposited thereinto.

It is believed in view of the foregoing description that a further detailed description 70 of the operation of the invention is entirely unnecessary. Likewise, it is believed that the advantages of the invention will be readily apparent.

As many changes could be made in the 75 above construction and many apparently widely different embodiments of this invention could be made without departing from the scope of the invention, and it is intended that all matter contained in the above description or shown in the accompanying drawings shall be interpreted as illustrative and not in a limited sense. It is also to be understood that the language used in the following claims is intended to cover all the 80 generic and specific features of the invention herein described and all statements of the scope of the invention which, as a matter of language might be said to fall therebetween. 90

Having thus fully described this invention, what is claimed as new and desired to be secured by Letters-Patent, is:—

1. A device of the character described including a base, a plate secured to the base 95 and bent to form spaced ribs and a groove therebetween, and a reticulated sheet having a roughened surface supported by the ribs and extending across and arranged in spaced relation with the groove. 100

2. A device of the character described including a base, a plate secured to the base and bent to form a pair of converging ribs and a groove between the ribs having an inclined bottom, a reticulated sheet having a 105 roughened surface bent and secured to the upper surface of the base about the plate and held in spaced relation to the groove by the ribs, and a cover plate having an opening therethrough secured to the base about 110 the reticulated sheet.

3. A device of the character described including a base, strips arranged in converging relation thereon, a plate secured transversely of the base, ribs formed in the plate 115 and arranged to straddle the strips and be supported by the latter, a portion of the plate between the ribs constituting a groove the bottom of which is inclined toward the wider end, a piece of screen secured about 120 the plate having its under surface contacting with the upper edges of the rib so as to be supported in spaced relation to the groove, and a cover plate having an opening therein secured to the upper surface of the base 125 about the piece of screen.

4. A device of the character described including a base, strips secured to the base and arranged in converging relation, a plate secured transversely of the base and bent to 130

straddle the strips to form ribs and a groove between the ribs, a piece of screen constituting a scraping surface extending across the plate and secured to the base, another piece of screen serving as a reinforcement to the first piece of screen extending transversely across the plate and the ribs so as to main-

tain the first piece of screen in spaced relation to the groove, and a cover plate having an opening therein secured to the base about 10 the first piece of screen, substantially as described.

In testimony whereof I affix my signature.
MARY L. WALTON.
